JAMES MAHONY, OF NEWPORT, RHODE ISLAND.

Letters Patent No. 91,949, dated June 29, 1869.

IMPROVEMENT IN STEAM-GENERATOR GRATE-BARS.

The Schedule referred to in these Letters Patent and making part of the same.

To all whom it may concern:

Be it known that I, JAMES MAHONY, of Newport, in the county of Newport, in the State of Rhode Island, superintending engineer of the Newport line of steamers between New York and Boston, have invented certain new and useful Improvements in Grate-Bars for Furnaces for Steam-Boilers and analogous situations; and I do hereby declare that the following is a full and exact description thereof.

My invention consists in the construction of all the several bars or parts of the compound grate-bar, herein described, in horizontal waves, or short curves or corrugations.

This construction maintains the arrangement of the parts in their ordinary positions, but allows for the contraction and expansion, under great extremes of temperature, without concentrating the strain at a few points.

The accompanying drawings form a part of this specification.

Figure 1 is a vertical section on the line S S in fig. 2.

Figure 2 is a plan view of part of a furnace.

Figure 3 is a side view, and

Figure 4, a plan view of my grate-bar, on a larger scale.

In these last figures, the wavy, or corrugated feature is applied upon a narrower section, and the grate-bar is reinforced or strengthened by a deep under-rib.

Deep under-ribs are not new. Neither is the widening or narrowing of the sections, or the diagonal position of the cross-bars in the section. But the forming of these several parts in short waves is new, so far as I am aware, and I find by practice that it is preferable to any other construction known to me.

Similar letters of reference indicate corresponding parts in the several figures.

A A is the exterior, or frame of each section, and

B B are diagonal cross-bars, cast in one with the surrounding frame A, and joined thereto at each end.

C C are projections extending outward, to hold the sections at proper distances apart, to allow air to rise between them; and

D D are bearers extending across underneath, and resting on the shelf in the side of the furnace.

In the form shown in figs. 3 and 4, a deeper central web or longitudinal part is cast in with the other parts, and is joined to the exterior frame A, and also to each of the cross-parts B, as indicated by E.

It will be observed that both the parts A and B are formed in short waves, or corrugations, as indicated by a b. These are curved so short, that a complete wave is formed in a length of bar of little more than twice the thickness.

The top of my sections is plane. I can slice in the ordinary manner. I can also introduce picks, devil's claws, and other cleaning-tools, in the ordinary manner, as the waves, or short curves, by reason of their being very short and small, do not interfere with the motion of cleaning-tools longitudinally of the slot, while they allow for the expansion or contraction at each bend, instead of concentrating it at the ends and middle, as when a general extended sweep is given to the bar.

I form my sections by moulding and casting from a pattern properly formed with the desired corrugations.

I am aware that many forms of grate-bar sections have been proposed, with curves and crooks in the several parts. These I do not claim. I do not claim anything shown in the patent of N. B. Schofield, May 1, 1866, or in that of J. R. Smith, November 5, 1867; the former having the corrugations only upon the lower and thinner web of the bars, and not producing the effect of my invention, and the latter having the curves in large sweeps, like the letter S, concentrating the flexion at the ends.

I am aware that many approaches have been before made to my improved construction, and I do not claim any of the features separately; but

What I claim, is—

The construction of the rectangular corrugated frame, with corrugated cross-bars and surrounding corrugated margin, as herein specified.

In testimony whereof, I have hereunto set my name, in presence of two subscribing witnesses.

JAMES MAHONY.
